UNITED STATES PATENT OFFICE.

OTTO L. OSTENDORF, OF ROCHESTER, NEW YORK.

FOOT-REST FOR RECLINING-CHAIRS.

1,185,819.

Specification of Letters Patent.

Patented June 6, 1916.

Application filed November 4, 1915. Serial No. 59,665.

To all whom it may concern:

Be it known that I, OTTO L. OSTENDORF, of Rochester, in the county of Monroe and State of New York, have invented certain new and useful Improvements in Foot-Rests for Reclining-Chairs; and I do hereby declare the following to be a full, clear, and exact description of the same, reference being had to the accompanying drawings, forming a part of this specification, and to the reference numerals marked thereon.

My present invention has for its object to provide a foot or leg rest mechanism for reclining chairs with the prime purpose in view of insuring comfort, and permitting adjustability of the rest with reference to the seat of a chair, for accommodating persons of different statures.

A further purpose of the improvement is to simplify the construction, and to reduce to a minimum the cost of manufacture, while at the same time permitting the device to be readily controlled and operated to bring the rest to its various positions, without incurring any particular discomfort to a person sitting in the chair.

To these and other ends the invention consists in certain improvements and combinations of parts, all as will be hereinafter more fully described, the novel features being pointed out in the claims at the end of the specification.

In the drawings: Figure 1 is a side elevation of a chair equipped with my invention, and showing the rest in operative position, in one position of adjustment, with the carrier in intermediate position. Fig. 2 is a bottom plan view. Fig. 3 is a view in side elevation, partially in section on line 3^a—3^a of Fig. 2; Fig. 4 is a view in side elevation, partially in section in a plane similar to Fig. 3, showing the carrier in its uppermost position, and the rest about to be moved to its uppermost position, and Fig. 5 is a detail view, in side elevation, showing the foot rest in another angular adjustment with relation to the seat, the carrier being in its outermost position.

Similar reference numerals throughout the several views indicate the same parts.

In the present embodiment of the invention, 1 designates the side pieces of the usual chair frame, upon which is mounted a seat frame carrying a seat portion 2, which may be arranged in adjustable relation with the

back of the chair, although this does not constitute any part of the present invention. The side pieces 1 are provided with guide ways 3, in which is mounted for slidable movement a carrier 4, having flanges 5 which engage the aforesaid grooves 3. The carrier 4 is movable forwardly and backwardly beneath the seat of the chair, its forward movement being limited by the cross-piece 6, which lies in the path of the stops, or projections, 7. The guide ways 3 are inclined upwardly from the back to the front of the chair frame so as to impart a corresponding slight upward movement to the carrier as the latter moves outwardly from beneath the seat, whereby the rest, which is to be described presently, is maintained in proper relation with the seat portion, and the closing movement of the carrier is made easier.

Pivoted on the carrier, near its forward end, is a supporting member consisting of side strips 8 and cross strip 9, the side strips 8 being pivoted to the side bars of the carrier, in the manner shown in Fig. 2.

10 designates the rest, which is pivoted at one edge of the cross strip 9 of the supporting member, and in such relation therewith that the rest extends equal distances on opposite sides of the supporting member when the parts are in locked engagement, thus affording a centralized and balanced point of support for the rest as well as a more compact arrangement in both its operative and inoperative positions. The rest carries a spring hasp 11, adapted to engage a coöperating projection 12 on one side of the cross strip 9 of the supporting member so as to hold the parts together, as shown clearly in Fig. 1. In this figure, the carrier is in intermediate position between its extreme inner and outer adjustments, and the supporting member is held against further outward movement relatively to the carrier by means of the front portion 13 of the latter, which engages the forward surfaces of the side strips 8 on the supporting frame. In this position, the rest 10 engages the seat in the manner shown in Fig. 1, and with the construction described, it is possible to arrange the rest at a different angle with relation to the seat as shown in Fig. 5 so as to accommodate different positions and persons of different stature. For this purpose, the

hasp 11 is released, freeing the rest from its supporting member, except where it is hinged to the latter, and permitting the supporting member to drop down. On moving 5 the carrier to its extreme outer position, the rest assumes the relation shown in Fig. 5, being supported at one end by the front edge of the carrier, and at its opposite end by the seat portion of the chair. By lifting 10 the rest from the position shown in Fig. 5 and then elevating its front end and depressing its rear end, the parts can be lowered until they assume the position shown in Fig. 3, with the rest housed within the 15 carrier and the supporting member underlying the rest, and, with the parts thus arranged, the carrier can be moved to its innermost position beneath the seat.

I claim as my invention:

20 1. The combination with a chair frame and seat, of a carrier slidably arranged beneath the seat for movement in and out, and a foot rest movably arranged on the carrier and having engagement with the seat at one 25 angle when the carrier is in one position and

at another angle when the carrier is in another position.

2. The combination with a chair frame and seat, of a carrier slidably arranged beneath the seat for movement in and out, a 30 supporting member movably mounted on the carrier, and a foot rest pivoted to the supporting member and adapted to be secured thereto whereby it may engage the seat either when the carrier is in its outermost position, or when the carrier is in an intermediate position, and the supporting member is released from the foot rest. 35

3. The combination with a chair frame and seat, of a carrier slidably mounted beneath the seat for movement in and out and a foot rest movably mounted on the carrier and adapted to engage the front edge of the seat at different angles for different positions of the carrier. 40

OTTO L. OSTENDORF.
